United States Patent Office

Des. 234,226
Patented Jan. 28, 1975

234,226

MECHANICAL PENCIL

Curtis L. Malm, Norwalk, and Henry J. Loewenthal, Woodland Hills, Calif., assignors to The Gillette Company, Santa Monica, Calif.

Filed Mar. 16, 1973, Ser. No. 341,888

Term of patent 14 years

Int. Cl. D19—06

U.S. Cl. D74—24

FIG. 1.

FIG. 2.

FIG. 3.

FIG. 4.

FIG. 5.

FIG. 1 is a rear elevational view of a mechanical pencil showing our new design;

FIG. 2 is a left side elevational view;

FIG. 3 is a front elevational view;

FIG. 4 is a top plan view thereof; and

FIG. 5 is an enlarged scale cross sectional view of the barrel taken along line V—V of FIG. 1.

We claim:

The ornamental design for a mechanical pencil, as shown and described.
